UNITED STATES PATENT OFFICE.

WILLIAM J. SULLIVAN, OF BESSEMER, ALABAMA.

MEASURING DEVICE.

1,226,722.

Specification of Letters Patent.

Patented May 22, 1917.

Application filed December 31, 1915. Serial No. 69,583.

To all whom it may concern:

Be it known that I, WILLIAM J. SULLIVAN, a citizen of the United States, residing at Bessemer, in the county of Jefferson and State of Alabama, have invented certain new and useful Improvements in Measuring Devices, of which the following is a specification.

This invention contemplates an improved measuring device and has as its primary object to provide a construction including a hopper adapted for attachment to a bin but which may, if desired, be used as an independent element in the capacity of a funnel and wherein the said hopper or funnel will be provided with a valve operable by a measuring cup adapted to be removably fitted into the hopper or funnel to engage the valve.

20 The invention has as a further object to provide a structure wherein the valve will be formed with lugs for positively limiting the valve in its movement to open and closed positions.

25 And a still further object of the invention is to provide a construction wherein the measuring cup will be uninterrupted at its upper margin so that the said cup may be filled to its capacity and wherein the cup 30 will be provided with lugs adapted to coact with the lugs of the valve for operating the valve.

Other and incidental objects will appear as the description proceeds and in the drawings wherein I have illustrated the preferred embodiment of the invention and wherein similar reference characters designate corresponding parts throughout the several views,

40 Figure 1 is a perspective view of my improved device showing the valve and cup detached from the hopper or funnel.

Fig. 2 is a vertical sectional view showing the manner in which the lugs of the cup are 45 adapted to coact with the lugs of the valve for operating the valve, and

Fig. 3 is a plan view showing the manner in which the lugs of the valve are adapted to engage the partition wall of the hopper 50 or funnel for limiting the valve in its movement to open or closed position.

In carrying out my invention, I employ a frustro conical hopper 10 which is provided with an annular spout 11 having a 55 bayonet slot 12 formed therein. Arranged within the hopper adjacent its smaller end,

is a partition or annular wall 13 which is provided upon opposite sides of its center with diametrically arranged openings 14. The hopper, the spout 11, together with the adjacent partition wall 13 may, if desired, all be formed of sheet metal although any other suitable material may be employed and upon an inspection of Fig. 2 of the drawings, it will be observed that the wall 13 is 60 not only connected at its periphery to the hopper but is arranged to seat upon the upper edge of the spout 11 to be braced and supported thereby.

Rotatably mounted upon the upper face 70 of the partition wall 13 is a valve 15. This valve is in the nature of a metal disk although the valve may be constructed of any suitable material, and is centrally pivoted to the partition wall 13, being connected to 75 said wall by a rivet 16 or other suitable fastening device and rotatable upon the said wall. Formed in the valve 15 upon opposite sides of the center thereof are diametrically arranged openings 17 adapted to register with the openings 14 in the wall 13, the valve, of course, being movable to close the openings in the said wall. Depending from the valve 15 upon opposite sides of the center thereof are diametrically arranged stop lugs 18 which are preferably integral with the said valve and are reversely presented with the outer faces thereof flush with opposite side edges defining the openings 17. The lugs 18 project through the openings 14 80 in the wall 13 and are adapted to simultaneously engage corresponding opposite edges of the said openings for limiting the valve 15 in its movement to open and closed positions respectively.

Associated with the hopper, is a measuring cup 19. This cup may also, if desired, be constructed of sheet metal although any other suitable material may be employed and is adapted to be removably fitted into the spout 11 in the manner illustrated in Fig. 2 of the drawings. Formed on the cup upon one side thereof is a stop lug 20 adapted to be freely received within the slot 12. At its open end, the cup is provided with oppositely disposed ears or lugs 21 secured to the inner face of the wall of the cup adjacent its outer margin and upon opposite sides thereof, the said lugs projecting inwardly toward the axis of the cup and having their outer faces flush with its upper edge. Formed in the ears 21, are diametri-

cally arranged radial slots 22, adapted to detachably engage the stop lugs 18 of the valve 15.

Normally, the valve 15 will rest upon the 5 wall 13 of the hopper in position, as shown in Fig. 3 of the drawings, to close the openings 14 in the said wall with the stop lugs 18 engaging one corresponding pair of side edges of the said openings. The cup 19 may 10 then be fitted in the spout 11 with the lug 20 of the said cup engaging in the slot 12 when the cup may be moved toward the wall 13 of the hopper to engage the lugs 21 of the cup with the lugs 18 of the valve 15, the lugs 18 15 being received within the slots 22 of the said first mentioned lugs. The cup 19 may then be turned in one direction within the spout 11 to rotate the valve 15 to open position with the lugs 18 of the said valve engaging 20 the pair of side edges of the opening 14 opposite to said first mentioned pair and with the openings 17 of the valve registering with the said first mentioned openings. The material to be measured will then flow 25 through the hopper into the cup when the cup will become entirely filled. The cup may then be rotated in the opposite direction to again move the valve 15 to closed position and since the outer faces of the lugs 18 are 30 flush with the adjacent side edges of the openings 17 in the valve, the valve may be shifted to a position to entirely close said openings.

It will therefore be seen that the stop lugs 35 18 serve a dual function in that they are not only adapted to positively limit the valve in its movement to open and closed positions respectively but are also adapted for engagement by the ears of the cup so that the 40 valve may be rotated. It will be noted that the valve 15 is arranged to rest upon the partition wall 13 of the hopper so that the weight of the contents of the hopper tending to press the valve down against the said 45 wall, will be supported by the wall and will not come upon the pivot 16 of the valve to hamper or impede the shifting of the valve to open or closed positions. It is further to be noted that the wall of the cup 19 at its 50 outer margin is uninterrupted or without openings so that the cup may be filled to its full capacity, this being an important feature in any instance where fine materials are to be measured. The device may, of course, 55 be constructed any desired size and may be used in any adaptation where found applicable. In this connection, it is to be pointed out that the hopper 10 may be secured to the bottom of a bin to surround an opening 60 therein so that the contents of the bin may run into the hopper. The cup 19 may then be employed to measure materials directly from the bin. For connecting the hopper with the bin, any suitable type of fastening 65 device may be employed. On the other

hand, the hopper can be used as an independent element in the capacity of an ordinary funnel.

Having thus described my invention, what I claim and desire to secure by Letters Patent:

1. A device of the character described including a hopper provided with a partition wall having an opening therein, a valve carried by said wall and provided with an opening, the valve being movable to one position to close the opening in the partition wall and to another position with the said openings registering, means carried by the valve for limiting the valve in its movement in opposite directions, and a vessel arranged for engagement with said means for operating the valve. 75

2. A device of the character described including a hopper having a partition wall provided with an opening, a valve carried by said wall and provided with an opening, the valve being movable to one position to close the opening in said wall and to another position with the said openings registering, a lug depending from the valve to project through the opening in said wall for engagement with opposite edges thereof for limiting the valve in its movement in opposite directions, and a vessel arranged 95 for engagement with said lug for operating the valve. 99

3. A device of the character described including a hopper provided with a wall having an opening therein, a shiftably mounted valve associated with said wall and provided with an opening, the valve being movable to one position to close the opening in the wall and to another position with the said openings in alinement, means carried by the valve and projecting through the opening in said wall for engagement with opposite edges thereof to limit the valve in its movement in opposite directions, and a vessel adapted for detachable connection to the hopper to engage said means for operating the valve. 103 108 110

4. A device of the character described including a hopper having a partition wall and provided with an opening, a valve carried by said partition wall and provided with an opening, the valve being movable to one position to close the opening in said wall and to another position with the said openings registering, a lug formed on the valve to depend therefrom at one edge of the opening in the valve with the said lug disposed for engagement with opposite edges of the opening in said partition wall for limiting the valve in its movement in opposite directions, a vessel, and a slotted ear carried by the vessel with the said slot receiving the said lug and with the cup operable for shifting the valve. 115 120 125

5. A device of the character described 130

including a hopper provided with a partition wall having an opening therein, a valve carried by said wall and provided with an opening, the valve being movable to one position to close the opening in the partition wall and to another position with the said openings registering, means carried by the valve for limiting the valve in its movement in opposite directions, a spout carried by the hopper and provided with a

bayonet slot, a vessel arranged for engagement with said means with the vessel operable within the spout for shifting the valve, and a lug carried by the vessel for engagement within said slot for locking the vessel 15 upon the spout upon the movement of the valve to open position.

In testimony whereof, I affix my signature.

WILLIAM J. SULLIVAN. [L.S.]
